DRUM WEIR

Daniel J. McCormack, York, Pa.

Application January 8, 1935, Serial No. 813

16 Claims.

(Cl. 61—28)

This invention relates to dams and more particularly to the type of dams known as drum weirs or roller gates.

5 Drum weirs or roller gates usually comprise a body adapted to be positioned across a stream or water course for the purpose of damming up the water, and these devices are furthermore adapted to be moved bodily from a damming position to another position in which the water is permitted to flow unimpeded down stream. Also, the main body portion of a drum weir may have one or more aprons or flaps secured thereto and extending therefrom for the purpose of increasing the damming height of the device.

10 15 The present invention is directed to the detail construction of the main body portion, and the apron or flap of a drum weir or roller gate.

An object of the invention is to provide an improved drum weir or roller gate in which the main body of the drum and the apron or flap extending therefrom have a minimum number of circular seams or joints.

20 Another object of the invention is to provide an improved drum weir or roller gate having a minimum length of all joints, and particularly a minimum length of circumferential joints.

25 Another object of the invention is to provide an improved drum weir or roller gate having a minimum number of sections of skin plate comprising the shell of the drum and apron or flap.

30 Another object of the invention is to provide an improved drum weir or roller gate of the character mentioned, which is simple in construction and reliable and exact in function under all conditions of service.

35 The invention also comprises certain new and useful improvements in the construction, arrangement and combination of the several parts of which it is composed, as will be hereinafter more fully described and claimed.

In the accompanying drawings:—

Figure 1 is an elevation looking at the upstream side of a drum weir or roller gate constructed according to the present invention and installed between two piers;

Fig. 2 is an enlarged view of the right hand end of the device shown in Fig. 1, the pier being shown in section;

Fig. 3 is a cross section taken on the line 3—3 of Fig. 1, showing the arrangement of the plates used in constructing the shell of the drum and the apron which is attached to the drum and depends therefrom, the reinforcing struts, etc., being omitted;

Fig. 4 is a view showing the arrangement of

the plates of the main body of the drum, the means for securing the adjoining edges of the plates together being omitted;

Fig. 5 is an enlarged section of a portion of the drum; and

Fig. 6 is a perspective of one of the plates used in forming the shell of the drum.

The main body portion of a drum weir or roller gate may consist of a cylindrical shell formed of a plurality of arcuate plates, and in cases where the drum is provided with aprons or flaps, the latter may consist of plates.

In constructing drum weirs, the shells or drums constituting the main body portions thereof, have been made in varying sizes and heretofore it has been the practice of the manufacturers and producers to construct the devices with the plate steel sheets curved or bent lengthwise. This mode of constructing the shells or drums, as well as the aprons or flaps attached thereto, results in a great many circumferential joints or seams when the plates are assembled together, especially in the longer devices, and a correspondingly fewer number of longitudinal seams or joints.

Furthermore, it is well known that the stresses at the circumferential joints materially exceed the stresses at the longitudinal joints of a drum or cylindrical shell-like device. Therefore, in order to have a strong and rigid structure, it has been necessary to employ much stronger fastening means along the circumferential joints or seams than along the longitudinal joints or seams.

Since it is much easier and less expensive to join together the straight abutting longitudinal edges of the several sheets of a large shell or drum, than the curved circumferential edges, it is obvious that the labor costs of the latter work greatly exceed the labor costs of the former work.

Also, by employing a preponderance of circumferential joints or seams in constructing a drum weir, as has been the custom in the past, the total number of feet of circumferential joints or seams to be formed will greatly exceed the total number of feet of longitudinal joints or seams, which also adds greatly to the manufacturing costs.

Therefore, it is of advantage to so construct a drum weir that the number and length of circumferential joints or seams is less than the number or length of the longitudinal joints or seams, so that the manufacturing and erecting costs will be correspondingly reduced below the costs of producing similar devices in the manner heretofore employed, and the following is a description of

one method by which the above objects have been attained.

While in the following description the term "apron" is used in referring to a portion of the drum weir structure, it is to be understood that such terminology also refers to the portion of the drum weir structure which is sometimes called the "flap", since both of these portions of the structure of a drum weir are usually arcuate in cross section and are usually constructed in substantially the same manner. In fact, in many instances, drum weirs may have both "aprons" and "flaps", the portions of the drum weirs constituting the "aprons" being the arcuate-shaped wing portions which extend or depend from the main body of the drums and have lower edges for seating on the sills of the masonry portions of the dams, and the portions termed the "flaps" being the arcuate-shaped hinged leaves mounted on the upper side of the drums and adapted to be swung away from and towards the drums, and when swung away from the drums constitute means for increasing the damming height thereof.

Referring to the drawings and especially to Figs. 1, 2, and 3, the drum weir or roller gate may comprise a cylindrical shell 16, which may have an arcuate apron 17 extending therefrom. While in the present instance a single apron 17 is shown, it will be understood that more than one apron or flap can be mounted on the shell 16 without departing from the spirit of the present invention.

The shell of the drum 16 is, as shown in Figs. 1 and 2, composed of end sections 18 and 19, and a plurality of intermediate sections 20, 21 and 22.

The end sections 18 and 19 are, respectively, partly disposed in niches 23 and 24, formed, respectively, in piers 25 and 26, constructed of reinforced concrete or any other suitable masonry material. The bottom of the niches 23 and 24 slope or are inclined, as indicated at 27, Fig. 2, so as to prevent the accumulation of water or ice in the niches.

Lying on the bed of the stream or water course and extending between the piers 25 and 26, is a sill 28, also constructed of reinforced concrete or any other suitable masonry material, as shown in Figs. 1, 2, and 3.

Mounted, respectively, on the end sections 18 and 19, are circular tracks 29 and 30, which tracks engage, respectively, tracks 31 and 32 mounted in the niches 23 and 24, respectively.

The tracks 29 and 30 are each formed with gear teeth 33 and 34, respectively, which teeth are in meshing relationship with teeth 35 and 36 formed on the tracks 31 and 32, respectively. The arrangement of the tracks and gear teeth are indicated by broken lines in Fig. 1 and these elements on the right end of the drum are clearly shown in Fig. 2.

The end section 19 is at the driven end of the drum weir, said end section having fixed thereto one end of a chain 37. The chain 37 is adapted to be drawn or pulled upwardly by suitable hoisting mechanism (not shown) and thereby roll the drum upwardly. Vice versa, said chain, when played out by the hoisting mechanism, permits the drum to roll downwardly towards its lower or damming position, in which position the lower edge of the apron 17 rests against the sill 28, as shown in Figs. 2 and 3. The drum rolls on the tracks 31 and 32, and the gear teeth 33 and 34, which are always in meshing relationship with the teeth 35 and 36, respectively, serve as means for guiding and retaining the correct vertical relationship of the two ends of the drum.

The end sections 18 and 19 of the drum are circular in form and may be constructed of reinforced plate steel in any suitable manner.

The segments of plate steel used in forming the cylindrical shell of the drum 16 and also the apron 17, are rectangular in form and in sizes up to the limit of facilities for making the plain steel sheets and the limit of facilities for fabricating the drum and the apron.

The intermediate sections 20, 21 and 22 of the drum constitute the main body or shell of the dam, and said sections are formed from sheets of plate steel which are fabricated in the manner to be hereinafter described. It will be appreciated that the plate steel shell is reinforced by means of struts, braces, etc. However, since the reinforcing means forms no part of the present invention, such reinforcing means has been omitted from the drawings and detail description.

As shown in Fig. 4 which represents a specific installation or design of a drum weir, eighteen sheets of plate steel are used in forming the intermediate sections 20, 21 and 22 of the drum. These plates are numbered from 41 to 58 inclusive, on Fig. 4 of the drawings, the sheets numbered 41 to 46 inclusive, being used in forming the section 20, the sheets numbered 47 to 52 inclusive being used in forming the section 21, and the sheets numbered 53 to 58 inclusive being used in forming the section 22. Obviously, other quantities of plates can be used depending upon the size of the drum weir, but in drum weirs of the type herein described it is most economical and expeditious to use a minimum number of circumferential joints, because the stress at the circumferential joints materially exceeds the stress at the longitudinal joints. Therefore, the cost of manufacture of a drum with a large number of circumferential joints is much greater than the cost of a drum having a minimum number of circumferential joints. A fewer number of pieces of plate steel will be required to form a drum having a minimum number of circumferential joints, and hence a fewer number of pieces means less work in the shop and less work at the site of erection.

In order to have tight fitting and rigid joints between the plates used in forming the drum, the marginal edges of each plate are machined smooth and straight, so that when the plates are assembled together in the arrangement shown in Fig. 4, the abutting edges of the plates will fit tightly together so as to form what is known as "butt joints". This is very important in the finished structure, since the drum will be stronger than in the case where rough and unfinished edges are placed together.

Furthermore, by first machining the edges of the plates smooth, all of the plates can be made the same size, so that when said plates are assembled together and arranged in the manner shown in Fig. 4, all of the longitudinal joints 59, 60, 61, 62, 63 and 64 will be, respectively, in substantially uniform straight lines, and all of the crosswise or transverse joints 65, 66, 67 and 68 will lie in substantially uniform straight planes.

When the drum is formed, the marginal edges 65 of the plates 41 to 46 inclusive, abut the inner circumferential edge of the end section 18, and the marginal edges 68 of plates 53 to 58 inclusive, abut the inner circumferential edge of the end section 19, as shown in Fig. 2. The longitudinal edges of plates 48, 52 and 58, abut the longitudinal edges of plates 41, 47 and 53, respectively, as indicated at 64, Fig. 3.

All punching, drilling, machining, planing, etc., is preferably done preparatory to shaping the plates.

The next step in the fabrication of the drum shell consists in bending each plate to the desired arcuate form, so that when the plates are assembled together, a cylindrical drum of true circular form and having the desired diameter, will be had.

Heretofore, when the plate steel shells were formed, it was the custom to bend the plates lengthwise or along their longitudinal axes, and the plates were assembled together so that the circumferential seams were along the longitudinal edges of the plates. This mode of constructing the drums resulted in a great many circumferential seams, especially in the longer dams, and a correspondingly fewer number of longitudinal seams.

However, according to the present invention, each steel plate is bent or curved crosswise or transverse of its longitudinal axis, as shown clearly in Fig. 6. The bending or forming may be accomplished by means of rolls, or in any other known manner.

After the plates have thus been formed, stiffening means, such as channel bars 79 are fastened to the underside thereof by any suitable means, such as rivets 71, as shown in Fig. 5.

When the curved plates are assembled together there will be a plurality of circumferential joints, as shown in Figs. 1 and 2, and a plurality of longitudinal joints, as shown in Figs. 1, 2, 3 and 5. These joints may be secured together in any known manner, such as by riveting, welding, etc.

One form of riveted joints is shown in the present instance (see Fig. 2), but it is to be understood that since the invention relates generally to the manufacture of devices along the lines of tanks, boilers, etc., any known method of fastening joints of plate steel together may be employed when desired, since this invention does not pertain to the manner of joining the plates together but relates more particularly to the manner of constructing a drum weir.

As shown in Figs. 1, 2, and 5, butt straps 72 and 73 may be used along the longitudinal joints, and said butt straps may be secured in place by a single row of rivets 74 on each side of the longitudinal joints, as shown best in Fig. 2.

As shown best in Figs. 1, 2, and 5, the circumferential joints may be fastened together by means of butt straps 75 and butt plates 76, and at the points where the circumferential joints intersect the longitudinal joints, additional plates 77 may be employed. The butt plates 75, butt plates 76 and the plates 77 are somewhat wider than the butt straps 72 and 73 heretofore referred to, so as to permit the use of double rows of rivets 78 on each side of the circumferential joints, as shown in Fig. 2.

Due to the bending movement incurred longitudinally of the drum as the result of the pressure of the water thereagainst, the stress at the circumferential joints is considerably greater than the stress at the longitudinal joints, hence in order to construct the circumferential joints strong enough to withstand the stress thereagainst it is necessary to employ double rows of rivets 78. Of course, when other securing means are used for joining the plates together it will be obvious that the circumferential joints will have to be constructed doubly stronger than the longitudinal joints in order to have a strong and rigid shell structure.

When rivets and plates are used for joining the

plates together the plates serve as means for sealing the joints as will be understood.

Since the apron 17 forms a component part of the drum weir, it is of advantage to also form the apron with as few circumferential or transverse joints as possible.

As shown in Fig. 1, the apron 17 extends from pier 25 to pier 26 and said apron is located on the upstream side of the dam. The apron 17 is composed of a plurality of steel plates which are fabricated and then assembled together in a manner substantially similar to that described above in connection with the description of the manner of fabricating and assembling the shell of the drum 16. Of course, with some designs of drum weirs it may be possible to employ a comparatively few number of sheets of plate steel for constructing the apron 17.

In the form of the invention illustrated in Figs. 1 and 3, the apron 17 is shown as being composed of eight sheets of plate steel, numbered in Fig. 1, 87, 88, 89, 90, 91, 92, 93 and 94, respectively.

These plates are first fabricated in the manner heretofore described, that is, their edges are machined smooth and straight, and the rivet holes formed therein. The plates are then bent or curved crosswise or transverse of their longitudinal axes to the desired curvature. The abutting longitudinal edges of the plates of the apron are then secured together by means of butt straps 75 and 88 and rivets 81, as shown in Fig. 3. The upper longitudinal edge 82 of plates 87, 89, 91 and 93 is fastened to the drum 16 by rivets 83. The transverse or circumferential joints of the plates are secured together by butt straps 84, as shown in Fig. 1, and these straps may be riveted together in the manner heretofore described. The lower edge of plates 88, 90, 92 and 94 of the apron 17 has a sealing strip 85 which is adapted to rest on an I-beam 86 embedded in the concrete sill 28 and thereby provide a tight seal for preventing water from passing under the dam, when the latter is in damming position, as shown in Fig. 3.

While in the present instance, the apron 17 is shown as having a longitudinal joint extending with the length thereof, it will be understood that in many instances the width of the apron will be such that a single plate can be used in lieu of the pairs of plates 87, 88; 89, 90; 91, 92; and 93, 94, shown in Fig. 1, since it may be possible to utilize plates wide enough to extend from the joint 82 to the lower edge portion having the sealing strip 85. In this latter case, providing the drum is extremely long, several such plates may be required in order to construct an apron which will extend the entire distance from one pier to the other of a dam. However, in such cases, the number of transverse joints will be a minimum and such number of joints will of course be less than the number of joints heretofore had when the plates were fabricated in the older manner.

In Fig. 1, the transverse joints of the plates comprising the apron are shown in staggered relationship to the circumferential joints of the shell of the drum. Such an arrangement of the joints between the plates of the shell and the plates of the apron may be desirable, since it is easier to assemble the parts at the site of erection and fasten them together.

Since the greatest points of weakness in drums and aprons of the type herein described, are along the circumferential joints, it has been necessary to materially reinforce such circumferential joints

so that the same will be strong enough to withstand the imposed stresses. For this reason, when the drums and aprons have been constructed in the manner heretofore customary, in which a large number of circumferential joints were employed, the cost of constructing these joints added considerably to the cost of the dams. It is well known in the art, that it is far cheaper to construct the longitudinal joints at the site of erection than the circumferential joints, since the workmen can work much better in a straight line throughout the length of the drum than around the circumference thereof. In prior devices the ratio of the intermediate circumferential joints to the intermediate longitudinal joints of the drums and aprons was from

20	2	10
	1	
to		
35	4	15
	1	
		15
		20

depending upon the overall dimensions of the drum weirs. According to the present invention, the ratio has been substantially reversed, and in drum weirs constructed according to my invention the ratio of the length of the intermediate circumferential joints to the length of the intermediate longitudinal joints will be from

30	1	25
	1.5	
to		
35	1	30
	3.50	

It is therefore apparent that by my invention a much stronger and more economical drum weir structure can be constructed, due to the fact that the number of feet of circumferential joints between the plates used in forming the drum weirs are considerably less than the total number of feet of longitudinal joints, and since the longitudinal joints can be formed and constructed much cheaper than the circumferential joints, the importance of the invention is readily apparent.

From the foregoing it will be noted that the total length and number of the longitudinal joints exceeds the total length and number of the transverse joints. This is desirable, since a stronger and more rigid drum weir structure will be had than is the case when the plates are bent the other way or lengthwise, in which latter case the length and number of the transverse joints will exceed the length and number of longitudinal joints.

While one illustrative embodiment of the invention has been described in detail, it is not the intention to limit its scope to that embodiment or otherwise than by the terms of the appended claims.

Having thus described my invention, what I claim is:—

1. A drum weir comprising a body composed of a plurality of plates, each plate being substantially straight lengthwise and being curved transversely of its length.

2. A drum weir comprising a cylindrical body composed of a plurality of plates and an apron fastened to said body, said apron also being composed of a plurality of plates, each plate having its major dimension lengthwise of the weir and its minor dimension transversely of the weir.

3. A drum weir comprising a cylindrical body composed of a plurality of substantially similar rectangular plates, each plate having its major

dimension lengthwise of the weir and its minor dimension transversely of the weir, all of the longitudinal joints between the plates being arranged in substantially straight lines, and all circumferential joints between the plates being arranged in substantially straight planes, the edges of said plates being butted together, and means for fastening the abutting edges of the plates together.

4. A drum weir comprising a plurality of arcuate plates fastened together along their adjoining edges, said plates being arranged with their edges lengthwise and crosswise of the weir structure, the ratio of the length of the circumferential joints between the plates to the longitudinal joints being from

20	1	10
	1.5	
to		
35	1	20
	3.50	

5. A drum weir comprising a cylindrical body composed of a plurality of substantially similar rectangular plates, said plates being assembled together with all longitudinal joints between the plates arranged in substantially straight lines, and all circumferential joints between the plates arranged in substantially straight planes, the ratio of the length of the circumferential joints to the length of the longitudinal joints being from

30	1	25
	1.5	
to		
35	1	35
	3.50	

6. A drum weir comprising a cylindrical body composed of a plurality of intermediate sections and opposite end sections, said intermediate sections being formed from plates, each plate being substantially straight lengthwise and being curved transversely of its length, all of the longitudinal joints between the plates being arranged in substantially straight lines, and all of the circumferential joints between the plates being arranged in substantially straight planes.

7. A drum weir comprising a cylindrical body composed of a plurality of intermediate sections and opposite end sections, said intermediate sections being formed from plates, each plate being substantially straight lengthwise and being curved transversely of its length, all of the longitudinal joints between the plates being arranged in substantially straight lines, and all of the circumferential joints between the plates being arranged in substantially straight planes, the ratio of the length of the circumferential joints to the longitudinal joints being from

60	1	50
	1.5	
to		
65	1	55
	3.50	

8. A device of the class described comprising a cylindrical body composed of a plurality of intermediate sections and opposite end sections, said intermediate sections being formed of a plurality of substantially similar plates of rectangular form, each plate being bent crosswise its length to provide an elongated arcuate sheet, all longitudinal joints between the plates being arranged in substantially straight lines, and all

circumferential joints between the plates being arranged in substantially straight planes and means for securing the adjoining edges of the plates together and to the end sections.

- 5 9. A drum weir comprising a cylindrical body composed of curved plates and substantially cylindrical end sections, said plates being arranged together whereby the length and number of longitudinal joints between the plates exceeds the 10 length and number of transverse joints between the plates, and means for joining the plates together and to the end sections to provide a strong and rigid structure.
- 10 10. A drum weir comprising a cylindrical body composed of curved plates and substantially cylindrical end sections, said plates being arranged together edge to edge with adjoining edges abutting, whereby the ratio of the length of the circumferential joints between the plates to the 15 longitudinal joints between the plates is

$$\frac{1}{1.5}$$

to

$$\frac{1}{3.50},$$

and means for securing the abutting edges of the plates together.

- 30 11. A drum weir comprising a cylindrical body composed of curved plates and substantially cylindrical end sections, said plates being arranged together edge to edge with adjoining edges abutting, the number of longitudinal joints between the plates exceeding the number of transverse joints, said plates being assembled together with 35 all longitudinal joints arranged in substantially straight lines and all circumferential joints arranged in substantially straight planes, the ratio of the length of the circumferential joints to the 40 length of the longitudinal joints being from

$$\frac{1}{1.5}$$

to

$$\frac{1}{3.50},$$

and means for securing the abutting edges of the plates together.

- 45 12. A drum weir comprising a cylindrical body and a flap connected to the body, said body and said flap being composed of a plurality of rectangular plates, each plate having its major dimension lengthwise of the weir and its minor dimension transversely of the weir, all of the 50 longitudinal joints between the plates being arranged in substantially straight lines, and all circumferential joints between the plates being arranged in substantially straight planes, the edges of the plates being butted together, and 55 60 means for fastening the abutting edges of the plates together.

13. A drum weir comprising a main body portion and an apron connected to the body, said body and said apron being composed of a plurality of arcuate plates fastened together along their adjoining edges, said plates being arranged with their edges lengthwise and crosswise of the weir structure, the ratio of the crosswise joints to the longitudinal joints being

$$\frac{1}{1.5}$$

to

$$\frac{1}{3.50}.$$

14. A drum weir comprising a cylindrical body and an apron connected to said body, said body and said apron being formed of a plurality of plates, said plates being assembled together with all longitudinal joints between the plates arranged in substantially straight lines, and all circumferential joints between the plates arranged in substantially straight planes at right angles to the longitudinal joints, the ratio of the length of the circumferential joints to the length of the longitudinal joints being from

$$\frac{1}{1.5}$$

to

$$\frac{1}{3.50}.$$

15. A drum weir comprising a body and an apron connected along one edge of said body, said body and said apron being formed of a plurality of substantially rectangular plates, each plate having its major dimension lengthwise of the weir and its minor dimension circumferentially of the weir, the ratio of the dimension of each plate lengthwise of the weir to the dimension of each plate circumferentially of the weir being from

$$\frac{1}{1.5}$$

to

$$\frac{1}{3.50}.$$

16. A drum weir comprising a cylindrical body and an apron depending therefrom, said apron being formed from a plurality of arcuate plates having one edge fastened to said body, each plate being substantially straight lengthwise and being curved transversely of its length, all of the longitudinal joints between the plates being arranged in substantially straight lines, and all of the circumferential joints between the plates being arranged in substantially straight planes, and the length of the longitudinal joints between the plates exceeding the combined length of all of the transverse joints between the plates.

DANIEL J. McCORMACK.
